UNITED STATES PATENT OFFICE

ARTHUR HAROLD LLOYD, OF COVENTRY, ENGLAND

SCREW-THREAD CUTTING DIE

Application filed October 18, 1929, Serial No. 400,614, and in Great Britain July 9, 1929.

This invention relates to dies for cutting screw threads, of the kind having segments with a leading cutting edge and a guiding portion which engages the newly cut thread and extends tangentially thereof (or approximately so) both in the leading and the following direction of the cutting movement.

The primary object of the invention is to provide means for rectifying the die segments by means of a lapping hob, in such a way as to eliminate any distortion due to hardening and to ensure that the correct helix angle of the die threads is maintained after sharpening so that a good finish is obtained at all times.

This and further objects and advantages of the invention will be apparent from the following description, in which reference is made to the accompanying drawings, where-

Figure 1 is a plan of a die segment engaged with a three-start-thread lapping hob adapted according to the invention,

Figure 2 shows a portion of a screw-thread cut by the die segment,

Figure 3 is a front view of the die segment,

Figure 4 is a diagrammatic representation showing an end view of the die segment cutting a screw thread (though the depth of the thread is actually ignored for the sake of simplicity, the thread being regarded as having no depth),

Figure 5 is a diagrammatic front view of the die indicating the area of contact between the die and the lapping hob, and

Figure 6 is a plan of part of a two-start-thread lapping hob with one of the start-threads missing.

In the construction described in the specification of British Patent No. 8806/04, die segments are provided with straight V grooves extending tangentially to the sides of the threads with which they are adapted to engage for guiding purposes. It will be understood, however, that the guiding effect obtained thereby is merely by a line contact at each thread because the latter is of helical form, whilst the groove sides are straight.

Thus, inaccuracy in the control of the thread formation can readily arise.

To overcome this difficulty, it has been proposed to use a lapping hob, having a thread corresponding to that of the screw to be cut, which hob is engaged with the previously-hardened die-grooves substantially as the work would engage with the latter, and is then charged with abrasive and oscillated about its axis (or rotated in opposite directions alternately) whilst the die segments are resiliently, or otherwise, fed inwards. This corrects the sides of the grooves so that they conform to the sides of the finished thread over considerable arcs and it provides accuracy of pitch and rectifies any distortion due to hardening. However, to avoid too close a contact of the die with the work, the hob had to be made of somewhat greater diameter than the screw to be produced, and consequently with a thread of smaller helix angle, which had the effect of producing a rough finish on the work.

In the attempt to overcome this difficulty, it has been proposed, during the lapping process, to incline the die segments to the axis of the oversize hob, but in such a case the die is only correctly disposed to the work in one position of its cutting edge, and when new. When re-sharpened an error is introduced which causes rough work.

In accordance with the present invention, a multi-start threaded lapping hob is used to correct the die, the effective diameter of the hob being a multiple of the effective diameter of the screw to be produced and the number of starts being equal to that multiple. In this way the helix angle of the hob can be the same as that of the screw to be produced but its diameter is considerably larger.

In one example, die segments to cut a $5\frac{1}{8}$ " screw with 11 Whitworth threads to the inch would be lapped with a hob having 11 threads to the inch and, say, two starts and of an effective diameter twice the effective diameter of the screw. Or, a hob with an effective diameter three times the effective diameter of the screw and with three starts could be used, and so forth, the multiples of the

effective diameter of the screw being the same as the number of starts.

To arrive at the "effective" diameter, the depth of the thread must be taken into consideration. For example, in the case of a $5/8$ " Whitworth screw, the outside diameter is .625" and the depth of the thread .058", making the "effective" diameter .567". The effective diameter of a two-start hob is twice this figure, i. e. 1.134", to which must be added the depth of the thread, making the overall diameter of the hob 1.192".

In the arrangement shown by Figures 1-5 of the drawings, where 2 represents the die segment, 3 the screw and 4 the lapping hob, the lapping hob is shown provided with a three-start thread, the respective starts being indicated by a dotted line 5, a broken line 6 and a full line 7. Assuming that there are in this case eleven threads to the inch on the screw and eleven grooves to the inch on the die segment, there are then $11/3$ threads to the inch in each start on the lapping hob.

In general, if there are m threads per unit length of the screw, there are m/n threads per unit length of each start, where n is the number of starts on the hob.

If d is the effective diameter of the screw 3 (being equal to the overall diameter less the depth of the thread) and D the effective diameter of the hob, then, in accordance with the present invention,

$$\frac{D}{d} = n,$$

or, in the case of the three-start thread shown in Figure 1, the effective diameter of the hob is three times that of the screw.

It will be realized from a comparison of Figures 1 and 2 that with this arrangement the helical angle of the screw is the same as the helical angle of the lapping hob.

In employing the hob 4, the die segments are arranged radially and with their grooves 20 in engagement with the threads on the hob, as indicated by Figure 1, and the hob is then rotated or oscillated whilst coated with abrasive in the well-known manner.

The threaded face of each die segment is usually milled at an angle to its flanks, and the segments must be so arranged with regard to the axis of the hob that a plane passing through the axis of the hob, and the ultimate axis of the screw to be produced, is at right angles to the effective plane in which the threaded grooves lie. As the lapping is effected without any inclination of the axis of the hob, the segment is uniform and correct through the whole of its life.

Figure 4 shows the effective plane 8, in which the grooves 20 of the die segment lie, disposed at right angles to the chain line 9 which represents a plane passing through

the axis of the hob (shown partly in chain line at 4) and the axis of the screw 3 to be produced. The effective plane 8 is slightly lapped away at the zone of contact 10 between the hob and the die; this zone of contact, for clearness, is shown in exaggerated form in Figures 4 and 5, the arrow 11 indicating the junction of the rectified portion with plane 8. In Figure 3, 12 indicates the rectified or threaded parts of the V grooves 20 of the die segment, the same being exaggerated for clearness.

It is obvious that in some cases one or more of the multi-threads 5, 6 or 7 can be removed and the hob 4 fed along axially to ensure that all the grooves 20 of the die will be rectified.

Figure 6 shows a two-start thread on a hob of effective diameter twice that of the screw to be cut, but one start-thread, indicated by the chain lines 13, has been removed. By rotating the hob with its remaining start-thread engaging the V grooves, the hob will travel axially with respect to the die segment and thus rectify all the grooves 20.

It is to be understood that slight variations from the foregoing dimensions may be adopted, for manufacturing reasons, without departing from the spirit of the invention.

What I claim as my invention and desire to secure by Letters Patent of the United States is:—

1. A method of rectifying, by the use of a lapping hob, a die segment for cutting a screw of effective diameter d with m threads per unit length, which involves the use of a lapping hob of an effective diameter of $n \times d$ where n is an integer greater than 1) and with m/n threads per unit length, substantially as described.

2. A method of rectifying, by the use of a lapping hob, a die segment for cutting a screw-thread, which involves the use of a multi-start-threaded lapping hob having an effective diameter the ratio of which to that of the screw to be cut is equal to the number of starts, substantially as described.

3. A method of rectifying a die segment for cutting a screw thread, by the use of a lapping hob having a number of starts of the thread equal to the ratio of the effective diameter of the hob to the effective diameter of the screw.

4. A method of rectifying a die segment for cutting a screw thread, by the use of a multi-start-threaded lapping hob having an effective diameter greater than the effective diameter of the screw and also having the number of starts of the thread equal to the ratio of the effective diameter of the hob to the effective diameter of the screw.

In testimony whereof I affix my signature.

ARTHUR HAROLD LLOYD. 133
